BABY PEN

Theophylus Foster Rose, Petersburg, Va.

Application April 6, 1956, Serial No. 576,653

2 Claims. (Cl. 5—99)

This invention relates to baby pens, and more particularly to the collapsible type.

One of the objects of this invention is the provision of a baby pen adapted to be collapsed so as to reduce the amount of space normally occupied by it when in folded or collapsed condition.

Another object of this invention is the provision of a baby or infant's pen adapted to be collapsed so it may be easily stored in a spaced area smaller than the space required for its normal intended use.

A further object of this invention is the provision of a baby pen that may be easily collapsed so as to be carried by an operative.

A still further object of this invention is the provision of a baby pen provided with transparent vented sides that permit an infant to be observed and be perceived while incarcerated in such pen, as well as to permit side ventilation.

Other objects and features will more fully appear from the following description and accompanying drawings, in which:

Fig. 1 is a vertical perspective view of the baby pen;

Fig. 2 is a perspective view showing a basal portion of the pen;

Fig. 3 shows a sectional view of a corner of a frame and plastic pane;

Fig. 4 is a sectional view taken along lines 4—4 of Fig. 3 looking in direction of the arrows;

Fig. 5 is a sectional view taken along lines 5—5 of Fig. 3 and showing a section of the plastic pane housed in a grooved section of a frame;

Fig. 6 is a perspective view of a latch;

Fig. 7 is a sectional view of the frames and latching means thereon;

Fig. 8 is a vertical perspective view showing the baby pen side sections folded in compact form, and

Fig. 9 is a vertical perspective view showing the baby pen basal sections folded in compact form.

Referring more particularly to the drawings, the invention consists of a plurality of frames 1, 2, 3, 4, 5, 6, 7 and 8; each frame being comprised of two sections, and said frames form the four sides of the pen. These frames may be constructed of any suitable material, such as plastic, light metal; but hardwood has been found to be the preferable material. The frames may be rectangular or square in shape and each of their corner (Fig. 3) sections are respectively secured together by a mortise 9 that registers with a tenon 10 to form a blind and tenon joint; both said members being glued together. A screw 11 is respectively secured to each section of the frame and the tenon thereby providing a firm and fast corner section.

Grooves 12 are respectively disposed in the inner medial edges 13 of each frame section and are adapted to accommodate transparent plastic sheets or panes 14. It will be noted that the tenons (Fig. 4) are also grooved and register with the companion frame grooves to accom-

2

modate the corners of the panes. Each of the frame sections is respectively provided with a plurality of pegs or lugs 15 secured in and projecting from the basal edges of each frame.

5 Frames 1 and 2 are secured to each other in pivotal fashion by a plurality of hinges 16 and the former is adapted to fold upon the latter in counter-clockwise fashion. Frames 2 and 3 are likewise secured to one another by hinges 17 and the former folds upon the latter in clockwise fashion.

10 Frames 3 and 4 are also secured to each other in pivotal fashion by hinges 18 and the former folds upon the latter in counterclockwise fashion. Frames 4 and 5 are pivotally connected by hinges 19 and the former folds upon the latter in clockwise fashion. Frames 5 and 6 are

15 connected together by hinges 20 and the former folds upon the latter in counterclockwise fashion. Frames 6 and 7 are pivotally connected by hinges 21 and the former folds upon the latter in clockwise fashion, and frames 7 and 8 are likewise connected by hinges 22 and former folds upon the latter in counterclockwise fashion.

20 It is thought obvious that when the frames are folded as previously described, they will nestle closely together in the manner clearly illustrated in Fig. 8. When the side frames are in compact form straps 23 are secured about the frames by buckles 24 and a hand grip 25 is secured to said straps in slidale fashion thereby affording expedient means of carrying or transporting the frames in a secure manner.

25 A base 26 is composed for four frames 27, 28, 29 and 30 that are constructed in similar fashion to the side frames except that each frame has a support bar 31 spanning its central portion. Frames 27 and 30 are secured together in pivotal fashion by hinges 32 mounted flushwise in the frames, while frames 29 and 28 are secured by hinges 33. Frames 29 and 30 are secured by hinges 34 disposed flushwise in the bottom of said frames.

30 Baseboards 35 are respectively secured to frames 27, 28, 29 and 30 by nails 35' or other suitable means to form the floor of said pen. Apertures 36 are respectively disposed in base 26 and are adapted to register with pegs 15 to prevent lateral displacement of the sides with respect to said base. When the base is desired to be folded in compact form frames 27 and 28 are folded upon

35 frames 29 and 30, and then frames 29 and 30 are folded upon one another. The base may be secured firmly in compact form by straps and buckles and provided with a handle as hereinbefore described. A plurality of orifices 37 are in each plastic pane for amusement of the confined infant and also to permit ventilation.

40 Frames 2 and 3, 4 and 5, 6 and 7 and 1 are respectively fastened by securing latch means 38 and since each is of similar structure the description of one (Figs. 6 and 7) is applicable to all. The securing means consists of a latch bar 39 having an aperture 40 in one of its ends and a countersunk slotted open eye 41 in the other of its ends. The latch, in this instance, is pivotally connected to frame 5 by a screw 42 engaging aperture 40 and anchored in said frame. A threaded bolt 43 is secured in frame 4 and projects upwardly therefrom and is adapted to engage eye 41. A washer 44 is disposed in the countersunk portion of the eye and a wing-nut 45 engages bolt 43 and is screwed tightly against washer 44 to prevent movement of frames 4 and 5.

45 It is though obvious that by the provision of these latches the central side sections will more firmly hold against any pressure on the sides.

50 The present vertical displacement securing means are provided in the nature of brackets 46 (Fig. 1) are of similar construction and description of one is applicable to the rest. The bracket is secured at the basal portion of the frame by nails 47 or any suitable means and is

provided with an open countersunk eye 48 of similar structure to eye 41 hereinbefore described, except that the bracket wherein the eye 48 is disposed is located in an angular leg 49. Threaded bolts 50 are respectively disposed in each of the basal frames and the eyes in brackets 46 are adapted to register with said bolts and wing nuts 51 are mounted on said bolts 50; thus securing the sides firmly to the base. It is to be observed that the legs 49 of the brackets pass under the basal portions of the side frames when they are folded so as to permit the latter to nestle snugly.

Having described this invention, what is claimed is:

1. A portable play pen for babies comprising a plurality of panel-like sides, hinged together in series fashion for folding in portable form when not in use, a plurality of basal sections hinged together alternately on top and bottom to form a base and adapted to be folded in portable fashion, brackets respectively engaging said sides and in operative relation with means on said base to prevent vertical displacement, and means respectively engaging the top middle portions of said sides to prevent arcuate displacement.

2. A portable play pen for babies comprising a plurality of sides hinged together in series fashion for folding in compact form when not in use; a plurality of sections hinged together in alternate fashion and adapted to form a base and to be folded in compact form when not in use; a plurality of brackets respectively engaging one side of said base and adapted for engagement with a plurality of bolts in said base, and means on said bolts for securing said brackets to said base so as to prevent

vertical displacement of said sides with respect to said base, and latching means on the top edges of said sides to retard arcuate movement thereof with respect to each other.
